UNITED STATES PATENT OFFICE

CLARENCE R. DAVIS, OF DETROIT, MICHIGAN, ASSIGNOR TO DAVIS TOOL & ENGINEERING COMPANY, OF DETROIT, MICHIGAN, A CORPORATION OF MICHIGAN

GARMENT RACK

Application filed February 23, 1929. Serial No. 341,937.

My invention relates to a garment rack for clothing stores, check rooms, or other places handling a relatively large number of garments that they may be easily accessible for examination or delivery.

One object of the invention is to provide a device capable of handling a large number of garments which may be hung from individual hangers suspended from the rack or the garments may be suspended directly from the bracket hooks forming part of the device.

Another feature of the invention consists in a novel check supporting clip carried by each hanger bracket, adapted to hold duplicate checks upright in such manner that the check room attendant may quickly and readily select the garment called for.

Another object of the invention is to provide a device of simple, rigid construction, pleasing in appearance and inexpensive to manufacture.

A further object of the invention is to construct the device entirely of metal, the upright posts and connecting bars upon which the bracket fixtures rest being made of sheet steel bent to form rectangular members when viewed in cross-section.

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

40 Figure 1 is a perspective view of the rack, with a portion of the connecting bars broken away that it may be shown in suitable proportion upon the sheet.

45 Figure 2 is an elevation of the hat bracket and check clip mounted on the supporting bar—shown in section.

Figure 3 is a plan view of the hat bracket, showing the supporting bar in dotted lines.

50 Referring now to the letters of reference placed upon the drawings:

A denotes a garment rack of substantially rectangular form, comprising a pair of standards, or posts B—B formed of sheet metal, connected together by upper and lower bars D, D¹, also formed of sheet metal, the ends of which extend through openings provided in the posts. The lower bar D¹ is relatively shorter than the upper bar D,—its purpose is to assist in stiffening the structure, making it more rigid. E are screws fastening the posts and bars together to form a unitary device.

F are cast metal bracket fixtures adapted to straddle the upper bar D, comprising depending hook-shaped portions F¹, extending in opposite directions to receive hangers for coats or other garments;—the garments however may be hung directly upon the hooks. Projecting upwardly at an angle from the hook-shaped portions and integral therewith are fingers F², to receive hats, caps, etc. G indicates a short post or pin, screwed into the top of the bracket, on which is mounted a spring clip H, to receive and grip numbered checks I, the arrangement being such that the check number may be easily read by the attendant in charge of the check room.

The standards A—A are mounted upon base plates J, J constructed of sheet metal in the form of a cross, the ends of the cross-members being bent downwardly, forming feet to support the base in spaced relation to the floor, with the long arms J^a, J^a of the respective base plates directed toward each other and parallel with the bars D, D¹.

These garment racks may be shifted about to suit any location and when used in department stores for displaying dresses or other garments, they may be arranged end to end in rows forming aisles of sufficient width to accommodate both salesman and customer when making inspection of garments with a view to purchase.

Having thus described my invention, what I claim is:

A garment rack, comprising a substantially rectangular frame consisting of a pair of posts formed of sheet metal, spaced apart and rectangular in cross-section; a pair of base plates for supporting the posts; a cross-

bar formed of sheet metal rectangular in cross-section projecting respectively through rectangular openings near the top of the posts; a plurality of supporting bracket fixtures comprising a central inverted U-shaped saddle portion adapted to straddle the rectangular cross-bars, each of said bracket fixtures having a pair of outwardly directed hooks projecting from each side of the saddle portion in superposed relation; a pin screwed through the upper wall of the saddle into said rectangular cross-bar to secure the bracket fixtures against displacement, a second cross-bar rectangular in cross-section extending through rectangular holes in the posts near the bottom of the latter; and set screws extending through the posts to secure the cross-bar to the posts.

In testimony whereof, I sign this specification.

CLARENCE R. DAVIS.
